UNITED STATES PATENT OFFICE.

HENRY F. HAGER, OF CHICAGO, ILLINOIS.

BED-SPRING FABRIC.

1,161,662.

Specification of Letters Patent. Patented Nov. 23, 1915.

Application filed February 18, 1915. Serial No. 8,999.

To all whom it may concern:

Be it known that I, HENRY F. HAGER, a citizen of the United States, residing in Chicago, in the county of Cook and State of Illinois, have invented a new and useful Improvement in Bed-Spring Fabrics, of which the following is a specification.

My invention relates in general to bed spring fabrics and has more particular reference to bed spring fabrics of the type of fabric commonly termed "square" and "rectangular" link.

The invention has for one of its objects the provision of a fabric of the character described, the links of which may be economically constructed and assembled.

The cost of bed spring fabrics is estimated roughly from the number of pounds of wire needed to form the complete fabric and it is an object of this invention to provide a fabric which will require in its formation a minimum weight of wire consistent with the production of an efficient and durable fabric.

A further object of the invention is to provide a noiseless fabric or more particularly a fabric in which the links will not rattle or make other noise when the fabric is in use on a bed or when it is being handled in selling.

A still further object of the invention is the provision of a fabric which may be secured in a bed spring frame by a variable number of helical springs of the usual type without altering the number of longitudinally disposed rows of links and without altering materially the form of the links of the fabric, alteration in the number of springs being accomplished by merely changing the length of the transversely disposed links without an appreciable alteration in strength and efficiency.

Other objects and advantages of the invention will be apparent as it is better understood from the following description when considered in connection with the accompanying drawing illustrating a preferred embodiment thereof.

On the drawing, Figure 1 is a partial top plan view of a bed spring embodying my invention; Fig. 2 is a vertical, longitudinal section of the same; and Fig. 3 is an enlarged detail perspective showing the construction of the links embodying my present invention.

For the purpose of illustrating my inven-

tion I have shown a bed spring fabric generally designated at A mounted in a frame B of usual or preferred type. As the form of this frame is unimportant from the standpoint of my invention, no detailed description of it is thought to be necessary. The fabric consists of links C which extend longitudinally of the bed and the fabric and links D which extend transversely thereof. The bed-spring fabric is positioned in the frame by helical springs 4 arranged one at each end of each row of longitudinal links C, one curved end 5 of the helical spring taking through the end of the end link and the other curled end 6 through a suitable aperture 7 in the frame.

The links C are in the present instance substantial duplicates of each other and a description of one of them will suffice for all. Each link C consists of a double wire body, the two legs or wires 8 of which are disposed side by side and in the finished fabric lie in the same horizontal plane. Each link C is made of a piece of wire and the legs 8 are connected at one end by a loop 9 which is preferably disposed in a vertical plane or rather in a plane at right angles to the plane of the legs 8. The other ends of the legs 8 are bent back upon themselves to form a double wire loop 10 disposed in the plane of the loop 9. The purpose of thus arranging the loops will be later disclosed.

The links C are arranged in longitudinal rows as has been said and they are connected together and held in place both longitudinally and transversely of the fabric by the cross links D which, like the links C are duplicates of each other. Each link D consists of a single strand body 11 terminating in an eye 12 at one end and in a loop 13 at the other, the eye and loop being arranged in different planes and preferably in planes at right angles of each other. The eye of each link D serves to connect two adjacent longitudinal links of the same row and to this end the double wire loop 10 and the loop 9 provided at adjacent ends of adjacent longitudinally disposed links are passed through the eye as seen in Fig. 3. This eye also engages within a loop 13 of a similar link D so that each eye 12 serves as a connecting eye for the four links meeting at the eye. This arrangement gives a substantially flat fabric, the double strands 8 of the body of the link C lying in a horizontal

plane in the finished fabric by reason of the arrangement just described prevents any pressure of one strand upon the other and prevents any noise of the strands moving 5 with respect to each other. The eyes 12 form parts of the longitudinal rows and consequently all of the links of the fabric feel weight when the spring is in use and at all times feel the tension of the helical springs 10 4 which prevents rattling of any of the links, the force of the helical springs 4 always being sufficient to prevent the action of gravity upon the links when the spring is up-ended or moved in other directions during selling. 15 A fabric composed of links embodying my invention can be readily and cheaply assembled as it is only necessary to thread each eye 12 first between the strands or legs of the body of a link C into its appropriate 20 loop 9 and to thereafter engage this eye 12 with the loops 10 and 13 of appropriate links by threading their ends 14 through the eye.

While any usual or preferred form of edging may be provided I show in the present 25 instance the band edge 15 connected by helicals 16 with the ends of the frame. This band is perforated at 17 for the reception of the loops 13, it being understood that at 30 the other edge of the fabric any expedient may be adopted to connect the band in place. The fabric is light and of pleasing appearance and it will be manifest that an elongation of the bodies 11 of the links D will permit the reduction of the number of helical 35 springs and shortening of them will correspondingly permit increase of their number.

It is thought that the invention and 40 many of its attendant advantages will be understood from the foregoing description, and it will be apparent that various changes

may be made in the form, construction and arrangement of the parts without departing from the spirit and scope of the invention or sacrificing any of its material advantages, the form hereinbefore described being merely a preferred embodiment thereof.

I claim:—

1. A fabric for a bed spring comprising a plurality of links arranged longitudinally in 50 rows extending lengthwise of the fabric and held under spring tension and a plurality of links arranged longitudinally in rows extending across the fabric, said last-mentioned links being each provided with 55 an eye in which are engaged the adjacent ends of two links extending longitudinally of the fabric.

2. A fabric for a bed spring comprising a plurality of links extending lengthwise of 60 the fabric and a plurality of links extending crosswise of the fabric and held under spring tension, the links extending crosswise having an eye forming a part of the longitudinal rows of links extending lengthwise 65 of the fabric.

3. A bed spring fabric comprising a pair of links extending longitudinally of the fabric and a link extending across the fabric and held under spring tension, said 70 link extending across the fabric having an eye connecting the adjacent ends of said links extending lengthwise of the fabric, said eye forming a part of a row of which the links extending longitudinally of the fabric are 75 a part.

Signed in the presence of two subscribing witnesses.

HENRY F. HAGER.
